UNITED STATES PATENT OFFICE.

FRED S. HERBERT, OF COLORADO SPRINGS, COLORADO.

HANDLE.

Application filed November 29, 1920. Serial No. 427,079.

To all whom it may concern:

Be it known that FRED S. HERBERT, a citizen of the United States, residing at Colorado Springs, in the county of El Paso and 5 State of Colorado, has invented certain new and useful Improvements in Handles, of which the following is a specification, reference being had to the accompanying drawings.

10 This invention relates to handles and particularly to handles for use in lifting filled sacks and like cumbersome articles.

An object of the invention is to provide a device of this character capable of being 15 readily applied to the arm and hand of a person to permit the person to obtain a firm hold upon the sack or the like.

Another object is to provide a device of this character which also protects the hand 20 and clothes of the user.

A still further object of the invention is to provide a device of this character having a hook member on one end adapted to engage the sack, and a hand grip carried by the device adjacent the hook member with which 25 the hand of the operator is engaged, the hook member serving to temporarily connect the device to the sack so as to permit the operator to handle the same as though 30 the hand grip was permanently connected to the sack.

With the above and other objects in view, the invention consists in the improved construction and arrangement of parts to be 35 hereinafter more particularly described, fully claimed and illustrated in the accompanying drawings, in which:—

Figure 1 is a side elevation of a handle constructed in accordance with an embodiment of the invention.

Figure 2 is a rear elevation, and

Figure 3 is a section taken on the line 3—3 of Figure 2.

Referring to the drawings, 5 designates a body member constructed from a single strip of material, said strip being substantially as wide as the hand of the person and of a length to extend from the palm of the hand to a point adjacent the elbow. The end portion 6 of the body member is extended back upon the front face 7 of the body member in angular relation thereto to provide a hook 8, said hook being adapted to extend a considerable distance beneath the sack or article 50 to be lifted to provide a substantial support for the sack. The end of the hook 8 is bead-

ed to prevent said end from damaging the sack. It is of course obvious that the body member is made of substantial material so that the weight of the sack will not distort 60 the hook.

The opposite end of the body member, is provided with an arm strap 10 which projects from the rear face 11 of the body member. This strap is secured to the face 11 and 65 is adapted to be passed around the arm of the user adjacent the elbow to hold the body member in the proper position on the arm of the user. The strap 10 is relatively wide, and has its end portion 12 reduced and provided with a buckle 13, while secured to the end portion 14 is a relatively narrow fastening strap 15. By this means the buckle and fastening strap do not come in contact with the arm of the user. At the same time the 70 broad strap is permitted to encircle the arm. In order to permit the operator to obtain a firm hold with the device, there is provided a U-shaped bracket 16, which is disposed adjacent the hook 8, and projects from the 75 lower face 11 of the body member. This bracket member may be riveted or formed integral with the member if desired.

Disposed between the ears 17 of the bracket is a hand grip 18, said hand grip 85 being disposed in spaced relation to the portion of the bracket connected to the body member so as to permit the hand of the user to pass between the hand grip and the body member.

It will be noted that the hand grip 18 and strap 10 project from the rear face 11 of the body member. Consequently, there are no projections of any kind on the front face 7 with the exception of the hook 8, so that 90 the sack may be properly positioned on the device without danger of the same being damaged. In addition to this, the hand of the user does not come in contact at any time with the sack as it is fully protected by the 95 body member.

To apply the device, the strap 10 is passed around the arm of the user adjacent the elbow while the hook portion 8 is positioned adjacent the palm of the hand of the user. 105 The strap 10 is then adjusted to properly position the body member on the arm. The device is then ready for use as all that is necessary is for the operator to grasp the hand grip 18, and insert the hook 8 beneath the sack to be lifted. This device will 110 be found especially useful in lifting cement

sacks as it protects the clothes of the user as well as the hands and at the same time permits a firm hold to be readily obtained on the sack in view of the length of the hook member 8. In addition to this the hook member 8 serves to temporarily connect the device to the sack so that the user may grasp the hand grip 8 as though it were permanently attached to the sack, it being impossible for the sack to slip.

From the foregoing it will be readily seen that this invention provides a novel form of handle which permits cumbersome objects that are difficult to handle to be moved readily from place to place without injury to the object or the hands and clothes of the person handling the same. In addition to this, it permits moving of these objects in considerable less time and with less labor than was possible heretofore.

What is claimed is:—

1. A handle of the character described comprising a plate having a hook member on one end thereof, fastening means carried by the opposite end of the plate for securing said plate to the arm of a person and a hand grip carried by the plate between the fastening means and said hook member.

2. A handle of the character described comprising a plate, one end of said plate being formed into a hook, means carried by the opposite end of the plate for securing said end to the arm of a person and a hand grip carried by the plate between the arm engaging means and the hook, said hand grip and arm engaging means extending in the opposite direction to that of the hook member.

3. A handle of the character described comprising a plate having a hook formed on one end and extended back upon the plate towards one face thereof, a strap carried by the opposite end and face of the plate and arranged to embrace the arm of a person, and a hand grip carried by the last mentioned face of the plate, adjacent the hook member.

4. A handle of the character described comprising a relatively broad plate having one end extended back upon the plate towards one face thereof to provide a hook, said hook extending laterally of the plate, a flexible arm strap immovably secured to the opposite end and face of the plate and arranged to embrace the arm of a person, and a bracket projecting from the last mentioned face of the plate, a hand grip carried by said bracket in spaced relation to the plate.

5. A handle comprising a relatively broad plate, having one end thereof extended in angular relation to the major portion of the plate to provide a hook or support, said hook or support substantially inclining toward the front face of the plate, a U-shaped bracket secured to and extending laterally of the rear face of the plate adjacent the hook or support, a handle member disposed between the arms of the U-shaped bracket in spaced relation to the body portion of the bracket, and an arm strap having one end portion thereof immovably secured to the rear face of the plate at the opposite end of said plate.

In testimony whereof I hereunto affix my signature.

FRED S. HERBERT.
